UNITED STATES PATENT OFFICE.

GEORGE D. GOODSPED, OF GARDNER, MASSACHUSETTS, ASSIGNOR TO HEYWOOD-WAKEFIELD COMPANY, OF BOSTON, MASSACHUSETTS, A CORPORATION OF MASSACHUSETTS.

HARNESS FOR REED-WEAVING LOOMS.

Application filed August 28, 1926. Serial No. 132,237.

This invention relates to improvements in harness for reed weaving looms and it consists in the matters hereinafter described and more particularly pointed out in the appended 5 claims.

In reed weaving looms employing a jacquard mechanism for determining the disposition of the various patterns or designs in the body of the woven fabric, great difficulty 10 is met with in providing a harness that will stand up under the action of the warp or filling strands, due to the large size and great strength of the warp or strand used in the weaving operation, as well as the necessary 15 close proximity of the filling strands to each other. The pull of such strands when employed in connection with a harness adapted for ordinary textile weaving, bends the heddles of such a harness so that they become 20 entangled and interfere with one another and render the loom inoperative.

The primary object of the invention is to provide a harness especially adapted for looms employing large warps or filler 25 strands and in which the heddles are so constructed as to amply withstand the pulling strain of the filler strands and will always remain straight and true.

Another object of the invention is to provide a strong and rigid heddle for the harness which may be readily made at a low cost and which cannot twist and bend in, but will freely 30 slide through the comber boards with which they are used.

A further object of the invention is to provide a heddle made from flat strip stock disposed edgewise in the plane of the warp or filler strands and which includes a suitable bearing sleeve disposed in a similar manner 40 and through which the strand may have a sliding guided movement.

These objects of the invention as well as others together with the many advantages thereof will more fully appear as I proceed 45 with my specification.

In the drawings:

Fig. 1 is a vertical longitudinal section through a reed weaving loom embodying my improved harness.

Fig. 2 is an enlarged detail sectional view of the heddles and associated comber boards shown at the middle top portion of Fig. 1.

Fig. 3 is a transverse vertical sectional view

view through the loom as taken on the line 3—3 of Fig. 1.

55

Fig. 4 is a fragmentary top plan view of one of the comber boards showing the disposition of the heddles therein.

Fig. 5 is a perspective view on an enlarged scale of the mid portion of one of the heddles.

60

Fig. 6 is a perspective view illustrating one of the steps in the making of the improved heddle.

The improved harness including the heddles is herein shown and will be herein described as embodied in a loom of the picker stick type but this is to be considered as by way of illustration only and not by way of limitation because the harness may be embodied in other kinds of looms where its peculiar characteristics make it of advantage to do so.

65

Referring now in detail to that embodiment of the invention illustrated in the accompanying drawings, 1 and 2 indicate respectively 75 the side frame members of a loom, which are suitably connected together in the desired spaced relation. At that end of the loom which may be termed the "rear" end is journaled a group of transversely extending guide and tension rolls 3, 4 and 5 respectively, about which a plurality of warp or filler strands 6 of fibre reed are trained from supply reels not shown. As said warp or filler strands pass about said rolls, they are in close 80 side by side engagement and extend forwardly from the guide rolls to pass through my improved harness indicated as a whole at 7 arranged between upright extensions 8—8 85 of the side frame members 1 and 2 respectively. 90

The harness includes transversely extending top, bottom and intermediate comber boards 9, 10 and 11 respectively and between said bottom and intermediate comber boards

95

is a plurality of heddle bars 12. Each heddle is in the form of a flat rod or bar 13 arranged edgewise in the planes of the strands, and said heddles have sliding guiding bearing in suitable openings provided therefor in the intermediate and bottom comber boards. Preferably, said comber boards are of metal and the bearing openings therein for said heddles are of a form corresponding to the cross section of said heddles so that the same 100 may freely slide therethrough without per-

105

mitting a twisting therein. In each bar substantially midway between the ends thereof, there is formed in the plane of the edges of the bar an opening 14 for the passage of a 5 filler strand therethrough. I find a convenient way to provide said opening, which is substantially of a diameter equalling the thickness of the bar by forming said opening in a sleeve 15 and affixing the portions 10 13^a—13^a of the bar thereto in any suitable manner. In Fig. 6 I have shown the bar parts 13^a—13^a and sleeve 15 in spaced relation as they appear in position of assembly and ready for attachment together preferably by welding or brazing. It is pointed out 15 that both ends of the opening 14 in said sleeve are flared outwardly so that no rough edges are presented to the associated strand as it passes through said sleeve, thus eliminating 20 roughing of strands and drag due to friction thereon.

The heddles each of which has a transverse hole through its top and bottom ends, are disposed in parallel rows, arranged at an angle 25 to the medium plane of the loom as best shown in Fig. 4. Adjacent filler strands are threaded through the bearing openings of the heddles in each angular row of heddles whereby the close side by side arrangement of the 30 strands are maintained in their passage through the harness.

The harness is actuated to control the shed formation of the strands by a jacquard mechanism 16 located above the loom as best shown 35 in Fig. 1. To the top end of each heddle is secured a neck cord 17 which extends upwardly through the top comber board 9. Said cords may be connected individually or in groups to the hooks 17^a of the jacquard mechanism which in turn are actuated by the usual 40 needles thereof. The positions of the needles, are in turn controlled by the usual chain of pattern cards 18 which pass over a cylinder 19 and these cards have needle openings 45 therein disposed collectively in accordance with the pattern to be produced in the fabric. The hooks are connected to a griffe 20 to which a rising and falling movement is imparted in any suitable manner, and at each rise and 50 fall the associated neck cords or group of cords is actuated to impart a similar movement to the heddles to which they are connected. The jacquard mechanism acts to lift the heddles upwardly, while a weight 21 operatively connected to the bottom end of each 55 heddle permits them to return to their lowermost position by gravity.

Forwardly of the harness is a longitudinal 60 reciprocating beam 22 which carries a reed 23. Said reed includes the usual open frame in which are located the usual closely spaced dents 24 between which the strands pass in said closely engaged relation. As shown herein said beam is mounted upon the top 65 ends of said arms 25—25 the bottom ends of

which are journaled on a cross shaft 26 mounted in the side frame members 1 and 2. In the forward movement of the beam, the reed acts to place or position a stake a predetermined distance from a previously inserted 70 stake 6^a and the fabric thus formed passes about suitable step by step rotated feed rolls 27 and 28 respectively to be wound upon the take up or fabric winding roll 29 all suitably mounted on cross shafts 27^a—28^a and 29^a 75 respectively at the forward end of the loom.

Forward and rearward reciprocating movement is imparted to the beam as follows:—30 indicates the main drive shaft of the loom which extends transversely of the loom and 80 is journaled in the side frame members 1 and 2 respectively. Fixed to said shaft between the side frame members is a cam member 31 having a cam groove 32. Operatively engaged on said shaft adjacent said cam is 85 the forked rear end of an arm 33 having a roller 33^a engaged in the cam groove. The forward end of said arm is connected to a rod 34 extending between and connecting the arms 25 of the beam together. In the rotation of 90 the drive shaft, the cam will, through the arm impart the desired movement to the beam with a dwell or momentary rest when the beam is in its normal rearward position.

Fixed on the end of the feed roll shaft 27^a 95 is a ratchet wheel 35 and loose on said shaft is an arm 36. Mounted on said arm is a pawl 37 operatively engaged with a ratchet wheel and connecting one of the beam arms 25 and said arm 36 is a link 38. Thus in each rearward movement of the beam after it has beaten home a stake, a step by step rotative movement is imparted to the feed roll. On the opposite end of the feed roll shaft is a pulley 39 and a belt 40 is trained about said 100 pulley 39 and about another pulley 41 fixed to the end of the take up roll shaft 29^a. By means of this belt the finished fabric is wound upon the take up roll as it is formed.

42 indicates a raceway member which extends laterally from and is fixed at one end to the side member 2 of the frame in substantially the plane of the beam 22 when it is in its normal position of rest. The other end of said raceway member is supported upon the top end of a standard 43 spaced laterally from the frame member 2. Slidably in said raceway is a shuttle block 44 and mounted on said block is the outer end of a gripper arm 45. The inner end of said gripper arm carries 110 pinching or gripping fingers 46 which are adapted when at the inner end of the movement of the gripper arm to grasp the end of one of a number of stakes 6^a arranged in a magazine 47 as best shown in Fig. 3. When the gripper arm moves in the other direction, after having pinched onto a stake, said stake is drawn through the shed and then released after which the reed moves forward 115 and locates the same in place. Thus in each 120

pick of the gripper arm a stake is removed from the magazine and inserted into the shed and after being positioned is locked in place by a reversal of the shed in the manner well known.

The gripper arm is connected by a link 48 to the top end of an arm 49 pivoted at its bottom end to the standard 43 as shown in Fig. 3. Swinging movement is imparted to the arm by means of a suitable link motion indicated as a whole by the numeral 50 and operatively connected up with gearing 51 driven from the drive shaft 30 all as best shown in Fig. 3.

The improved harness set forth as embodied in the loom above described has many advantages. The heddles thereof are strong and rigid and amply withstand the strain imposed upon them in use, without bending and without the usual entanglement.

While in describing my invention, I have referred to certain details of mechanical construction as well as form and arrangement of the parts thereof, I do not wish to be limited thereto except as may be pointed out in the appended claims.

I claim as my invention:—

1. A weaving machine for a stake and strand fabric embodying therein top, bottom and intermediate comber boards, non-flexible heddles having a sliding guiding bearing in said bottom and intermediate comber boards, neck cords operatively connected to the top ends of said heddles and extending through the top comber board and weight members secured to the bottom ends of said heddles below said bottom boards, each heddle having an eye between its ends for the passage of a strand member therethrough.

2. A harness for a loom embodying therein

comber boards, heddles each comprising a flat bar having sliding bearing in said comber boards and each heddle having a centrally disposed warp eye therein between its ends for the passage of a strand, said opening being disposed in the plane of but midway between the sides of the heddle.

3. A harness for a loom embodying therein comber boards, heddles each comprising a flat bar having sliding bearing in said comber boards and each heddle having a thickened part at a point between its ends with a warp eye therein, disposed in the plane of the sides of said heddle.

4. A harness for a loom embodying therein comber boards, heddles each comprising a flat bar having sliding bearing in said comber boards and each heddle having a thickened part at a point between its ends with a warp eye therein, disposed in the plane of the sides of said heddle, the ends of said opening being flared outwardly.

5. A heddle comprising a flat bar having transverse openings at each end to receive neck cords and lingoies respectively, and a sleeve at a point between said ends, there being a warp eye in said sleeve arranged in the plane of the sides of said bar.

6. The method of making a heddle which consists in providing a sleeve with a warp eye opening therein and two flat bar members and in securing an end of each bar member to opposite side of said sleeve and in alignment with each other and with the edgewise plane of said bars parallel with the warp eye opening in said sleeve.

In testimony whereof, I have hereunto set my hand, this 24th day of August, 1926.

GEORGE D. GOOD SPEED.
